(57) **CLAIM**

The ornamental design for a phototherapy pad control unit, as shown and described.

DESCRIPTION

FIG. 1 illustrates a top perspective view of a phototherapy pad control unit;

FIG. 2 illustrates a front view of the phototherapy pad control unit thereof;

FIG. 3 illustrates a back view of the phototherapy pad control unit thereof;

FIG. 4 illustrates a left side view of the phototherapy pad control unit thereof;

FIG. 5 illustrates a right side view of the phototherapy pad control unit thereof;

FIG. 6 illustrates a top view of the phototherapy pad control unit thereof; and,

FIG. 7 illustrates a bottom view of the phototherapy pad control unit thereof.

The broken lines shown in the drawings are included for illustration purpose only and form no part of the claimed design.
